UNITED STATES PATENT OFFICE.

FRANCESCO SAVERIO CALISE, OF PROVIDENCE, RHODE ISLAND.

FUEL-IGNITING DEVICE.

No. 890,212.

Specification of Letters Patent.

Patented June 9, 1908.

Application filed January 14, 1908. Serial No. 410,759.

To all whom it may concern:

Be it known that I, FRANCESCO SAVERIO CALISE, a subject of Italy, residing at the city of Providence, in the county of Providence and State of Rhode Island, have invented 5 certain new and useful Improvements in Fuel-Igniting Devices, of which the following is a specification, reference being had therein to the accompanying drawing.

10 This invention relates to fuel igniting devices and has for its object to provide a simple, inexpensive and convenient device for igniting the coal in a stove direct without the use of paper, wood, coke, or other kindling 15 material.

My improved device is a portable frame to which a flexible gas pipe is connected. This frame is adapted to be inserted into the ash pipe below the grate of any ordinary stove 20 and is provided with a plurality of adjustable tips or burners which may be set to project up between the bars of the grate.

By the use of my improved device no kindling material is required. The coal is poured 25 into the stove directly onto the grate and after lighting the burners in the frame and inserting the same into the stove beneath the grate, the plurality of powerful blue flames which are forced with considerable pressure 30 from the jets, spread themselves all through the body of the coal, thoroughly igniting the same in a very few minutes. After the coal is burning properly the gas is turned off and the igniting device removed.

35 With these and other objects in view, the invention consists of certain novel features of construction, as will be more fully described and particularly pointed out in the appended claims.

40 In the accompanying drawings: Figure 1—is a sectional view of a stove showing my igniting device in position to fire the coal. Fig. 2—is a perspective view of the igniting device removed from the stove and the 45 burner tubes removed from the frame. Fig. 3—is a sectional view of a portion of the frame showing one of the offset burner tubes in one position and dotted in another position. Fig. 4—is an enlarged detail view of 50 one of the offset burner tubes. Fig. 5—is a central sectional end view of the frame showing the standard for supporting the device in

the stove. Fig. 6—is an enlarged view showing a detail of the gas and air inlet.

Referring to the drawings at 1 is represented an ordinary kitchen stove with the front portion broken away, showing the firebox 2, ash pit 3 and the grate bars 4 in section, the coal being piled up at 5 on the grate ready to be lighted by my improved igniting 60 device.

This device is preferably constructed of a hollow rectangular frame 6, the same being provided with a channel 7 around through it forming substantially a square tube for the 65 passage of gas, but a tubular member of any form may be made to serve my purpose.

Threaded holes 8—8 are formed a short distance apart in the upper face of this frame 70 communicating with the passageway, and into these holes are screwed the offset tubular burners 9. These burners are offset for the purpose of adjustment so that they may be turned or rotated in their respective holes in the frame into any desired position, and 75 set so as to project up between the grate bars 4 close under the coal in the fire pot.

A hollow externally threaded boss 10 is formed on one side of this frame onto which is screwed a short tube 11. The outer end 80 of this tube is provided with openings 12—12 through which air is drawn by the force of the gas flowing therethrough from the jet nozzle 13, forming a powerful blue flame at the burners. The quantity of gas flowing to 85 these burners may be nicely regulated by the stop cock 14, the gas being led thereto from any convenient source (not shown) through the flexible pipe 15. On the lower side of this frame is a boss 16 into which is threaded 90 a standard 17. The lower end of said standard is adjustably supported in a set of legs 18 and is retained at the desired height by means of the set screw 19.

This device is of extremely simple and 95 practical construction, is very effective in its operation, and by its use the fire in a stove may be kindled quickly and with comparative ease.

Having thus described my invention, what 100 I claim as new and desire to secure by Letters Patent, is:

A device of the character described comprising a portable tubular frame adapted to

be readily inserted into the ash pit of a stove, said frame being provided with a plurality of adjustable gas burners adapted to pass up between the grate bars, a tube connected to said frame provided with openings, a gas jet nozzle in said tube adapted to draw in sufficient air to cause a blue flame when burning, a flexible supply pipe connected to said tube, and a vertically adjustable stand-

ard for supporting said frame in said pit 10 whereby the coal in the stove may be ignited without the use of kindlings.

In testimony whereof I affix my signature in presence of two witnesses.

FRANCESCO SAVERIO CALISE.
